DESIGN.

J. L. FOLSOM.

CARPET.

No. 18,138.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,138, dated March 6, 1888.

Application filed January 26, 1888. Serial No. 262,061. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists, principally, of a number of circular flower forms connected by a vine-work, which also supports intervening leaf forms and bunches-of-fruit forms or pebble-

like ornamentation. The flower forms have a 20 cup-shaped flower center surrounded by long and slender and pointed petals or flower-leaves. These flower forms are shown in various positions, some in full, others in profile. The pebbled or fruit work is gathered in very irregular masses around different parts of the vine-work or the flower forms. Between the flower forms are separate leaves occurring at intervals along the vine-work.

What I claim as new, and desire to secure 30 by Letters Patent, is—

The design for carpets, consisting of the design substantially as shown.

JAS. L. FOLSOM.
